No. 36,465.

Patented July 28, 1903.

UNITED STATES PATENT OFFICE.

OVID COHEN, OF NEW HAVEN, CONNECTICUT.

DESIGN FOR A BOOK AND PAPER CUTTER.

SPECIFICATION forming part of Design No. 36,465, dated July 28, 1903.

Application filed June 27, 1903. Serial No. 163,443. Term of patent 3½ years.

To all whom it may concern:

Be it known that I, OVID COHEN, a citizen of the United States, residing at New Haven, in the county of New Haven and State of Connecticut, have invented and produced a new, original, and ornamental Design for Book and Paper Cutters, of which the following is a specification, reference being had to the accompanying drawings, forming a part thereof, and in which—

Figure 1 is a plan view showing the front of my design; Fig. 2, a plan view showing the back of my design.

What I claim, and desire to secure by Letters Patent, is—

The ornamental design for a book and paper cutter as shown.

In witness whereof I have hereunto set my hand, at New Haven, in the county of New Haven and State of Connecticut, this 22d day of June, 1903.

OVID COHEN.
